DESIGN FOR A DESK

Charles I. Center and Wilson E. Tarr,
South Bend, Ind.

Application February 12, 1941, Serial No. 98,963

Term of patent 14 years

To all whom it may concern:

Be it known that we, Charles I. Center and Wilson E. Tarr, citizens of the United States, residing in South Bend, in the county of St. Joseph and State of Indiana, respectively, have invented a new, original, and ornamental design for a Desk, of which the following is a specification, reference being had to the accompanying drawing, forming a part thereof.

In the drawing:

The present design is characterized by a desk of the type disclosed, having no center drawer, and wherein the flat top substantially overhangs the two sides and the front of the desk, all as shown.

We claim:

The ornamental design for a desk, as shown and described.

CHARLES I. CENTER.
WILSON E. TARR.
